UNITED STATES PATENT OFFICE.

WILLIAM S. BREEDEN, OF MILLVILLE, NEW JERSEY.

DESIGN FOR A BOTTLE.

Application filed July 23, 1923. Serial No. 6,838. Term of patent 14 years.

To all whom it may concern:

Be it known that I, WILLIAM S. BREEDEN, a citizen of the United States, residing at Millville, in the county of Cumberland and State of New Jersey, have invented a new, original, and ornamental Design for Bottles, of which the following is a specification, reference being had to the accompanying drawing, forming a part thereof in which—

Figure 1 is a side view of a bottle shaped in accordance with my new design, and

Figure 2 a horizontal section through the bottle shown in Figure 1.

I claim:

The ornamental design for a bottle substantially as shown.

WILLIAM S. BREEDEN.
